KNIFE SUPPORT FOR AXMINSTER LOOMS

Julius H. Pfau, Yonkers, N. Y., assignor to Alexander Smith, Incorporated, a corporation of New York

Application February 28, 1950, Serial No. 146,865

2 Claims. (Cl. 139—7)

1

This invention relates generally to carpet looms of the Axminster type. More specifically the invention relates to the manner of attaching the knives to the knife bars or beams.

In Axminster looms the yarn is fed from a plurality of spools arranged in a row and is inserted in the backing material, after which the yarn is cut from the spools by a pair of cooperating knives which extend across the width of the loom. These knives must be kept in accurate alignment and register to produce a uniform pile. In the relatively wide Axminster looms in general use today it is necessary to provide very stiff and rigid beams or bars for carrying the knives. If the beams are very limber any vibration will separate the knives so that complete cutting across the loom will not be obtained. On the other hand, it has been found that with the knives rigidly secured to stiff, heavy beams any vibration is likely to break the knife blades.

According to my invention I provide a flexible mounting for securing a knife blade to a stiff, heavy, rigid beam which eliminates all danger of blade breakage due to vibration of the beam and permits the loom to operate at a much higher speed than was previously possible.

The principal object of my invention is to provide a knife blade mounting which will eliminate all danger of blade breakage due to vibration.

Another object of the invention is to provide a knife blade mounting which will assure more accurate cutting and thereby produce a more uniform pile.

Still another object of the invention is to provide a knife blade mounting for Axminster carpet looms which is so constructed and arranged as to permit a higher operating speed than was previously possible.

Other and more limited objects of the invention will be apparent from the following specification and the accompanying drawings forming a part thereof wherein:

Fig. 1 is a fragmentary transverse section through a portion of an Axminster carpet loom showing my invention incorporated therein;

Fig. 2 is a plan view of the back beam removed from the loom and showing a knife blade secured thereto according to my invention; and

Fig. 3 is a vertical sectional view taken on the line 3—3 of Fig. 2.

Referring to the drawings by reference characters, the numeral 1 indicates a portion of one of the side frames of an Axminster carpet loom. A reed or comb 2 is suitably supported by a lay 3 which is mounted for forward and backward

2

movement upon arms 4. A tube frame 5, carrying spools 6, is secured to actuating levers 7. The parts thus far described and the operating mechanism therefor are of standard well known construction and form no part of my invention. Consequently they are not shown and described in more detail herein.

A back beam 10 is slidably mounted at the ends thereof in the usual guide-ways or blocks 11 which are secured to the side frames of the loom. The beam 10 is reciprocated in the guide-ways 11 by standard mechanism, not shown, through connecting rods 12. A front beam 13 is mounted for rocking movement upon the upper ends of pivoted levers 14. A knife blade 15 is rigidly secured to the under-side of the front bar 13 by a plurality of bolts 16.

The back beam 10 comprises the base 17 and the flange 18 which is integral with the base 17 and extends upwardly from the rear edge thereof. The ends 19 of the base 17 beyond the ends of the flange 18 extend into the guide-ways 11.

A knife blade 22 which cooperates with the blade 15 is rigidly secured by a plurality of bolts 23 to the underside of a blade holder 24. The blade holder 24 is pivotally secured to the underside of the base 17 of the back beam 10 by a piano hinge 25 which extends the full length of the blade holder 24 intermediate the side edges thereof. A plurality of equally spaced studs 26 are rigidly secured to the blade holder 24 in a row adjacent the rear edge thereof. The studs 26 extend upwardly, from the blade holder 24, through apertures 27 in the base 17 of the rear beam 10 and into elongated apertures 28 in the bottom leg of an angle iron 29 which is secured to and extends the length of the flange 18 of the back beam 10. Each stud 26 has a nut 30 and a washer 31 adjustably mounted thereon. A tubular section of sponge rubber 32 is disposed about each stud 26 between the washer 31 and the underside of the bottom leg of the angle iron 29. The sponge rubber sections 32 acting through the studs 26 and blade holder 24 resiliently hold the knife blade 22 in proper position with respect to the knife blade 15. The normal position of the blade 22 can be accurately adjusted by the nuts 30. If desired soft springs may be substituted for the sponge rubber sections 32.

With this construction and arrangement I am able to use stiff rigid beams without danger of breaking or separating the knife blades by vibration during operation. This principle of stiff support with local flexibility of the blade

enables a loom to be operated at much higher speeds than was previously possible.

While I have shown and described my improved blade mounting as applied to the back beam of a loom, it will be obvious to those skilled in this art that it can be applied equally well to the front beam; and it is to be understood that I am not limited to the specific construction shown and described as various modifications may be made therein within the spirit of the invention.

What is claimed is:

1. In a knife blade mounting for an Axminster carpet loom the combination of a knife beam having a base and an outwardly extending flange, a knife blade holder, a hinge by which said holder is secured to the underside of said base, a knife blade rigidly secured to said holder at one side of said hinge, a plurality of studs rigidly secured to said holder at the other side of said hinge, said studs extending upwardly through apertures in said base, and resilient means engaging said flange and said studs and operative to yieldingly maintain said holder and said blade in normal position.

2. In a knife blade mounting for an Axminster carpet loom the combination of a knife beam

having a base and an outwardly extending flange, a knife blade holder, a hinge by which said holder is secured to the underside of said base, a knife blade rigidly secured to said holder at one side of said hinge, a plurality of studs rigidly secured to said holder at the other side of said hinge, said studs extending upwardly through apertures in said base and into apertures in an angle bracket secured to said flange, an adjustable stop on each 10 of said studs, and resilient means mounted on each of said studs between said adjustable stops and said bracket, said resilient means being operable to maintain said holder and said knife blade in normal position.
